UNITED STATES PATENT OFFICE.

HARRY F. ROACH, OF ST. LOUIS, MISSOURI.

DETERMINATION OF STRESSES AND MOVEMENTS.

Application filed November 12, 1921. Serial No. 514,522.

To all whom it may concern:

Be it known that I, HARRY F. ROACH, a citizen of the United States, residing in the city of St. Louis and State of Missouri, have 5 invented new and useful Improvements in the Determination of Stresses and Movements, of which the following is a specification.

This invention relates to a process for determining the maximum stress in the fibres of a member which is subjected to a load; and for investigating the effect of wheel loads and track reactions. While the invention may be employed to determine stresses 10 in practically any structure in which a substantial distortion occurs, it is most useful in investigating rail stresses due to bending moments developed in rails by the passing trains. Many attempts have been made to 15 determine such stresses from the bending moments calculated from the known weights upon axles, and similar data, but the manner in which the roadbed reacts to the weight upon the rail is of the greatest importance in such calculations. The effects 20 from this factor are very difficult to determine, due largely to the fact that the character of the roadbed is quite variable. Even where the material which forms adjacent 25 portions of the roadbed is the same, nevertheless its resistance and reaction under load may vary considerably. For example, a portion of the track may be supported on solid ground and an adjacent portion on a fill. 30 Indeed a large proportion of railway roadbed is built upon fill, which is a condition which is also favorable to the occurrence of high variations in the resistance factor or reaction under load. Another factor of 35 importance is that of drainage, and where the drainage is not good, there would naturally be a great decrease in the reactive qualities of the roadbed. When one considers that in a single rail length great variations in the 40 nature of its support may occur, it is obvious that under the modern practice of heavy loads, very unusual and abnormally high stresses may occur at certain localities on the roadway. It has also been attempted 45 to determine the action of the ballast under a passing load by means of pressure capsules which are supposed to indicate the pressure developed in the ballast, but the use of such instruments necessitates the removal and replacement of the ballast and 50 hence the test conditions are obviously not

the same as those existing in the ballast before it was removed.

The general object of the present invention is to produce a simple process and apparatus for investigating relatively small movements of a body, and to determine maximum stresses in a loaded member. As applied to a railway track, my process enables the actual distortions and stresses under the load to be accurately determined in a very simple and expeditious manner.

The invention consists in those novel steps and combination of steps, all of which contribute to produce a simple and efficient process for investigating stresses and determining the maximum stress in a structure subjected to load; and the invention also resides in the apparatus, means, diagrams or graphs which result from the use of the process. A preferred embodiment of my invention will be particularly described in the following specification while the broad scope of my invention will be pointed out in the appended claims.

Further objects of my invention will appear hereinafter.

In the drawing—

Figure 1 is a diagrammatic plan indicating how my process is practiced on a railway track;

Figure 2 is a vertical section diagrammatically illustrating the special means which I may employ to effect magnification of the rail distortions under the action of a load;

Figure 3 is a diagrammatic view illustrating the magnified variation of a portion of track from a horizontal line or axis; and

Figures 4, 5 and 6 constitute a series of diagrams or graphs corresponding to different positions of a passing load and graphically indicating the distortions corresponding to the assumed position for the load.

In practicing my process I produce a representation of the member while subjected to the load, but in this representation I magnify the distances in the direction in which the distortions of the member occur by reason of the load; the representation is preferably simply a photograph taken with a special lens attachment which effects the magnification of all distances or measurements in the desired direction.

If it is desired to produce a still greater magnification of the distortions the photo-

graph may be rephotographed one or more times. Supposing that the lens produced a magnification of five times in the original photograph, it is evident that if the original photograph were rephotographed three times a magnification of 625 times would be produced in the final photograph.

In the case of a structure that is simply subjected to a fixed load, it is merely necessary to photograph the member while subjected to the load. This would be all that would be necessary in a member which is disposed upon an absolutely straight line when not subjected to a load. However, as few members subjected to stress are actually straight when not loaded, it is advisable in order to produce an exact representation of the distortion, to photograph the member while it is at rest, that is to say, when not subjected to its load. This photograph should be rephotographed in the same manner as described above. In this way two representations or photographs are produced, one of which shows the modified distortions of the member under its load and the other shows, what might be called, the magnified profile of the member. By combining these two photographs it is possible to determine exactly what the real distortion of the member is under the load.

While my process may be used in this simple way to determine the stresses in a member carrying a fixed load it is particularly useful and serviceable where the member is subjected to a live load; for example, for determining the stresses in track rails developed by a passing train. I shall now describe the process in detail as applied to this purpose.

In Figure 1, 1 may represent a given length of a piece of track and, for example, we may assume that the distance between the two points 2 and 3 is fifty feet. If it is desired to investigate the stresses between these points I set up a camera, preferably a moving picture camera 4 at a sufficient distance away from the track to take in the required fifty feet.

The camera is provided with means for focusing the light rays from the object, in combination with a cylindrical member operating to effect a relative magnification of all dimensions of the object in the direction in which the movements occur. If a lens is used for focusing the rays then the camera should be provided with a special lens or special attachment for the lens which will effect relative magnification of all distances in the direction in which distortions occur. In the present instance these distortions, of course, would occur in a vertical direction and the optical system is so constructed as to magnify all vertical distances. A simple lens arrangement for accomplishing this is illustrated diagrammatically in Fig. 2. In

this view 5 represents an achromatic lens which is mounted on a telescoping sleeve 6 so as to enable the lens to be moved in order to focus the image of the rail on the film 7 which is mounted in the camera. This film 70 may be driven in the usual way by means of a crank 8. In the fixed barrel 9 of the camera I mount a special lens 10 which is provided with curved faces, that is to say, cylindrical concave faces 11 and 12; these 75 faces 11 and 12 are of the nature of cylinders, that is to say, the horizontal elements of the surface are parallel to a fixed or horizontal axis, but their distance from this axis varies as may be necessary to produce the 80 desired relative magnification. It should be noted that I use the term cylindrical in its geometric sense. In this way, a ray 13 of light coming from the rail 14 would pass through the opening 15 of the stop or dia- 85 phragm 16 and after passing through the lens would be refracted in the manner indicated in Figure 2. In this way the photograph taken upon the film would magnify all vertical distances and hence would produce a magnification of any distortion or 90 vertical movement which occurred in the rail as the load passed over it.

With a magnifying attachment of this nature, if a photograph were taken of a rail, or a certain length of track, the profile of the rail would be found not to be in a straight line, but an irregular line, such as the line 17 (see Fig. 3). This line might have the relation indicated with respect to the horizontal or straight line 18. Having taken a single photograph of the track so as to establish the magnified profile 17 of the rail, I then take a series of pictures of the track length while the train is passing 105 over it.

In Figures 4, 5, and 6, 19 represents a load such as a locomotive and these three figures correspond to different progressive positions of the load in passing along the track. Of course, in practice these pictures would be made at the rate of sixteen or more per second, and would, therefore, give a complete indication of practically all rail distortions which would have occurred while the load 115 was passing. However, Figure 4 merely represents the load after it has passed about one-quarter of the length being investigated, while Figure 6 shows the load at about the last quarter of its movement. Figure 5 120 shows the load in mid-position.

In Figure 5 the line A—B represents the rail profile at the instant that the load is at the middle of the length or stretch being investigated, but, of course, with the 125 vertical distances greatly magnified. However, it should be understood that this line A—B would not accurately represent the distortion of the rail unless the rail was in a straight condition. In order to produce 130

an accurate representation of the actual distortion it is necessary to combine the characteristics of the line A—B with the line 17 so as to produce a resultant line C—D. The 5 line C—D is plotted by using ordinates such as the ordinate y on Figure 3. At a corresponding point on Figure 5 the point 20 is found by measuring down from the line

A—B a distance equal to the ordinate y . 10 In this way a diagram, graph or curve is plotted which represents the distortion in the rail profile from the normal condition of rest. Where there is a sharp bend in this 15 line a relatively large fibre stress is indicated; for example, at the bottom of this curve such a bend occurs. By drawing a tangent and a line at right angles to it the relation of the distances indicated by the letters c and h on the figure can be obtained 20 and from this data the fibre stresses may be readily computed by any of the well known formulas. Of course, in all computations the co-efficient of magnification must be used 25 as a divisor to obtain a correct expression of the actual stress.

It will be noted that the use of my process does not require any reference of the curve or graph to any axis. It is merely necessary to produce a representation of the rail profile under the load. According to my method it is also not necessary to compute the 30 stresses indicated at all of the points where bends occur. This arises from the fact that it is merely necessary to compare the different photographs with each other to ascertain which photograph shows the sharpest curve in the distortion line. For example, in Figure 4, the full line E—F represents the resultant distortion line after combining 35 the photograph with the normal profile line 17. This line E—F may exhibit a very sharp bend at the point 21. The corresponding bend or dip in the line C—D is indicated by the dotted line at 22 and hence it is 40 very evident that the stress corresponding 45 to this load position of Figure 4, developed in the rail is very much greater than that developed as indicated in Figure 5.

To further illustrate this point, the distortion line G—H shown in Figure 6 may 50 present a sharp bend at the point 23 which might indicate a fibre stress far greater than those indicated by the other figures.

In this way it will be evident that by preparing 55 a series of these distortion graphs, diagrams or photographs corresponding to successive or progressive positions of the load passing over the rails, the different diagrams may be readily compared with each 60 other by superposing them upon each other. This, of course, would be facilitated by forming the diagrams upon transparent or translucent paper. By comparing the diagrams 65 very accurate information results as to the point of maximum stress in the rail.

It is also evident that by using the same load with different types of wheels, the influence of the different wheels on the track-reaction will also be indicated by the diagram, that is to say, by comparing a diagram produced with one wheel, with a diagram produced by using the same load with another wheel. 70

My process enables the action and reaction of the wheels on the track to be investigated in case the wheel should leave the track for an instant. In such a case the magnification of the ordinates in the photograph will indicate the position of the wheel. Knowledge of this nature might 75 lead to many deductions as to track reactions at the locality photographed.

It is evident that my invention may be used for investigating relatively small movements of a body where the movements are 80 not cause by stresses.

It is understood that the embodiment of the invention described herein is only one of the many embodiments my invention may take, and I do not wish to be limited in the 85 practice of my invention nor in my claims, to the particular embodiment set forth.

What I claim is:

1. The process of determining the maximum stress in a member carrying a live 90 load which consists in producing a series of representations showing a given length of the loaded member with the load in different positions, in which the distances are magnified in the direction in which distortions 95 occur due to the load, comparing the representations to ascertain the point of maximum indicated distortion among the representations, and then computing the 100 fibre stress corresponding to the maximum indicated distortion. 105

2. The process of determining the maximum stress in a member carrying a live 110 load, which consists in producing a series of photographs of a given length of the member with the load in different positions, and in which the distances represented in the photographs are magnified in the direction in which distortions occur due to the load, comparing the photographs with each other to ascertain which photograph and what point upon the same indicates the maximum distortion and then computing the fibre stress corresponding to the maximum indicated distortion. 115

3. The process of determining the maximum stress in a member carrying a live load, which consists in producing a representation showing a given length of the unloaded member, in which the distances are magnified in a direction substantially at 120 right angles to the longitudinal axis of the member, producing a series of representations showing the same length of the member with the load in different positions 125 130

- in which the distances are likewise magnified in a direction at right angles to the longitudinal axis of the member, producing a series of diagrams in which each diagram 5 is the result of the combination of the first representation with one of the series of representations, so that each diagram correctly indicates the actual distortion in the member due to the load, comparing the series 10 of diagrams with each other to ascertain the maximum indicated distortion in the whole series, and then computing the fibre stress corresponding to the maximum indicated distortion.
- 15 4. The process of determining the maximum stress in a member carrying a live load, which consists in producing a photograph showing a given length of the un- 20 loaded member in which the distances are magnified in a direction substantially at right angles to the longitudinal axis of the member, producing a series of photographs showing the same length of the member carrying a load in progressive different 25 positions, in which the distances are like-wise magnified in a direction at right angles to the longitudinal axis of the member, producing a series of diagrams in which each diagram is the resultant of the combination 30 of the first named photograph with one of the series of photographs so that each diagram correctly indicates the actual distortion in the member due to the load, comparing the series of diagrams with each 35 other to ascertain the maximum indicated distortion in the whole series of diagrams, and then computing the fibre stress corresponding to the maximum indicated distortion.
- 40 5. The process of determining the maximum rail stress in a given length of track, which consists in producing a series of photographs showing a given length of the track with a load in different progressive positions 45 passing over the track, in which the vertical distances are magnified, comparing the photographs of the series with each other to ascertain the point of maximum indicated distortion among the series, and then computing the fibre stress corresponding to the maximum indicated distortion.
- 50 6. The process of determining the maximum rail stress in a given length of railway track which consists in producing a photograph showing a given length of the track without a load on the rails, in which the vertical distances are magnified, producing a series of photographs showing the

same length of track with the load in different progressive positions in which the 60 vertical distances are likewise magnified, combining each photograph of the series with the first named photograph to produce a series of diagrams in which each diagram correctly indicates the actual distortion in 65 the rail due to the load, comparing the series of diagrams with each other to ascertain the maximum indicated distortion in the whole series of diagrams, and then computing the fibre stress corresponding to the 70 maximum indicated distortion.

7. The process of investigating stresses in a member subjected to a load which consists in producing a photograph of the member when not subjected to the load, in which 75 distances are magnified in the direction in which distortions under the load will occur, producing a second photograph of the member while subjected to the load, in which distances are likewise magnified in the direction in which distortions occur, and plotting a diagram which is the resultant of the two photographs, said diagram indicating the 80 actual distortion of the member under the load.

8. The process of investigating stresses in a member subjected to a load which consists in producing a series of photographs of the member in which distances parallel to an axis of selection are magnified in the direction only in which distortions under the load occur, and ascertaining the stresses through the agency of the indicated distortions in 90 the photograph.

9. In processes of investigating stresses 95 photographically, the step of producing a photograph of the member while subjected to the load, in which distances parallel to an axis of selection are magnified in the direction only in which the distortions of 100 the member occur under the action of the load, and then computing the fibre stress corresponding to the distortion of selection.

10. The process which consists in investigating minute movements in a member by 105 producing an image of the member while subjected to the influence of an affecting force, in which image distances are magnified in the direction only in which the selected movements occur which are parallel 110 to an axes of selection, and thereupon observing such magnified movements during their occurrence.

In testimony whereof, I have hereunto set my hand.

HARRY F. ROACH,
